George C. Heinricke

UNITED STATES PATENT OFFICE.

WILLIAM HENRY SCHAEFER, OF NEW YORK, N. Y.

INHALER.

1,375,325.

Specification of Letters Patent. Patented Apr. 19, 1921.

Application filed June 29, 1920. Serial No. 392,762.

To all whom it may concern:

Be it known that I, WILLIAM HENRY SCHAEFER, a citizen of the United States, residing at New York, county of New York, 5 and State of New York, have invented certain new and useful Improvements in Inhalers, of which the following is a specification.

The object of the present invention is an improvement in inhalers of the type desired in my co-pending application, Serial No. 301,534 filed June 3rd, 1919, of which this is a continuation in part.

It is the object of my invention to provide an inhaler of a very simple and compact construction which can be readily carried by the user on his person and which is constructed of a non-corrosive material so that it will not be injurious in any way to a patient.

A further object of the invention is the provision of an inhaler in which the material absorbing the medicament is contained in a perforated and split metal sleeve constituting means for conveniently holding the inhaler tube in its socket, thus making the provision of special fastening means unnecessary.

These and other objects will become apparent as the description of the inhaler proceeds reference being had to the accompanying drawing, in which—

Figure 1 is a side elevational view showing a modified form of construction, parts being broken away.

Fig. 2 is a transverse sectional view taken on line 2—2 of Fig. 1.

Fig. 3 is a detail view of the sleeve holding the medicated material and its socket, the parts being assembled.

Fig. 4 is a similar view with the parts separated, and,

Fig. 5 is a rear view of the inhaler.

Fig. 6 is a plan view of the sleeve or tube.

Referring to the drawings in detail, the numeral 10 indicates a hollow cylindrical body preferably made of glass, having an open lower end, the upper end being contracted upon opposite sides and formed integrally with the contracted portion 11, are a pair of slightly conical tubes 12, separated by the space 13, and containing relatively small orifices 14, the tubes being so positioned as to readily enter the nostrils of an ordinary person.

Integrally formed with the cylindrical body 10 is a curved hollow arm or tube 25, the element 25 extending upward from said body and merging with the curve 27 into the mouth engaging portion 28, terminating in a substantially ball-shaped enlargement having a frontal opening 29. The body 10 preferably has an open lower end and at its upper end is formed into a pair of slightly conical tubes 12 separated by the space 13 and containing relatively small orifices 14. The tubes 12 being so positioned as to readily enter the nostrils of an ordinary person. The lower end of the inhaler is constituted by a socket or cap 30 having a flange 31 adapted to be engaged by the thumb and fingers of an operator, and extending inwardly from the cap is an annular resilient sheet 32 having a plurality of perforations 33. The resilient sheet 32 is slotted and rolled up into a tube having its slotted ends 34 and 35 overlapping the other ends, the ends 34 and 35 being separated by a horizontal slot 36 so that the ends are adapted to spring outwardly and engage with the interior wall of the cylindrical body 10, and of the cap 30 so as to be held firmly in engagement therewith.

The sheet or sleeve 32 is adapted to receive a cellular substance 37 as sponge or the like, previously impregnated with any desired medication whatever.

In operation, the nasal tubes 14 having been placed in the nostrils, the device may be used as a simple inhaler by inspiration of the breath through the nostrils, in which case the air, laden with the medications will pass through the passages of the nose or the same may be forced through, by blowing in the tube 25, creating sufficient pressure to force the medicated air through the passages without inspiration.

From the foregoing it will be seen that a neat and effective device for the purpose has been disclosed which due to its construction is readily amenable to ordinary cleansing purposes; that when used in combination with suitable drugs will be found highly effective in ailments of the throat and nose, such as headaches, neuralgia, hay fever, colds, catarrh, asthma, and the like, and that the device may be used repeatedly or continuously as desired.

It is to be understood that the inhaler body, while preferably made of glass, por-

100

105

110

celain or like material, may also be constructed of metal of a non-corrodible nature, or plated so that the drugs or medicaments used have no effect upon the same.

5 The disclosure is to be regarded as descriptive only and not as restrictive or limitative of the invention, of which obviously an embodiment may be constructed including many minor modifications without departing from the general scope herein indicated and hereinafter claimed.

10 I am aware that various devices for similar purposes have been the subject of prior invention and can be found upon the market, 15 and I do not desire the present invention to be confounded therewith, but what I do claim as new and desire to secure by Letters Patent is—

1. An inhaler comprising a cylindrical 20 body, a pair of conical tubes formed integrally therewith, a hollow mouth-piece integral with said body, a flanged cap at the lower open end of said body, and a perforated and slitted sheet, said perforate 25 sheet being rolled up into a tube with its slitted end overlapping the other end, the tube being carried by the cap and adapted to receive cellular material impregnated with a medicament.

30 2. An inhaler comprising a cylindrical body, a pair of nostril engaging tubes formed integrally therewith, a hollow mouth stem secured in a plane at right an-

gles to said tube, a flanged cap adapted to receive the lower open end of said body, 35 resilient means engaging with said cap whereby said cap is held in its body engaging position, constituting a perforate split sheet rolled up into a tube with its slit- 40 ed end overlapping the other end, the tube being carried by the cap and adapted to receive a means removably engaged in said tube for holding medicaments.

3. An inhaler of the character described, comprising a cylindrical body, a pair of 45 nostril engaging tubes integrally formed with said body, a hollow substantially S-shaped stem on said body, a substantially ball-shaped mouth-piece at the upper end of said stem provided with a round opening at 50 its frontal end part, a flanged cap adapted to engage the lower end of the said body, a perforated metal sheet rolled up into a tube with one end overlapping the other end, the tube being carried by the cap and adapted 55 to receive the medicated material, said overlapping end being divided by a horizontal slot into two parts, the upper part to engage the inner wall of said body and the lower part to engage the inner wall of said cap for 60 firmly holding the parts together with frictional contact.

In testimony whereof I have affixed my signature.

WILLIAM HENRY SCHAEFER.
